UNITED STATES PATENT OFFICE.

ROBERT W. SCOTT, DECEASED, LATE OF BABYLON, NEW YORK, BY CHARLES B. BARNES, OF HINGHAM, MASSACHUSETTS, CHARLES J. McDERMOTT, OF BROOKLYN, NEW YORK, AND HARRISON G. REYNOLDS, OF BOSTON, MASSACHUSETTS, EXECUTORS, AND ALBERT E. PAGE, OF BROOKLYN, NEW YORK; SAID SCOTT AND SAID PAGE ASSIGNEES TO SCOTT AND WILLIAMS, INC., OF NEW YORK, N. Y., A CORPORATION OF MASSACHUSETTS.

PATTERN CONTROL MEANS FOR KNITTING MACHINES.

Original application filed August 29, 1924, Serial No. 734,888. Divided and this application filed May 15, 1925. Serial No. 30,570.

Our invention relates to knitting machines and more particularly to pattern control means therefor. The invention is particularly useful in the making of stripes in stockings containing plated fabric, but it has many other applications. One object of our invention is to provide a machine which produces a long series of pattern changes properly coordinated with the control of the basic pattern movements; and another object of this invention is to provide improved mechanism which is capable of producing a large variety of patterns. The machine includes a ratchet and pawl-operated pattern control means, independent idling means, and other idling mechanism therefor having angular motion. The invention will be described in connection with the process and mechanism for producing plated horizontal stripes in hosiery which forms the subject matter of the patent to said Robert W. Scott and Albert E. Page 1,666,794 dated April 17, 1928 of which this is a division.

For purposes of illustration we have shown our invention embodied in a seamless hosiery machine of the well-known Scott & Williams type.

In the accompanying drawings—

Fig. 1 is a side elevation in section through part of the head of a knitting machine showing the yarn guides and the levers controlling them;

Fig. 2 is a side elevation on a smaller scale of the pattern drums controlling the yarn guides;

Fig. 3 is a plan view of our yarn tension-changing means;

Fig. 4 is a front elevation of our yarn tension-changing means showing part of the wave of the needles;

Fig. 5 is a plan view of the throat plate showing the yarn guides in one radial position;

Fig. 6 is a similar plan view with the yarn guides in the reverse radial position;

Fig. 7 is an elevation of the hook of a needle showing how the yarns are fed to the needles

when the yarn guides are in the positions shown in Fig. 6;

Fig. 8 is a view similar to Figure 7 taken when the yarn guides are in the position shown in Fig. 5; and

Fig. 9 is a detail elevation of the mechanism controlling the movement of the striping pattern drum.

As is well understood, in the plating the two different yarns are fed to the needles in such a way that one yarn will be regularly drawn to the face of the knitted fabric and the other yarn will be drawn to the back, both yarns being preferably knit by every needle. It has heretofore been suggested that reverse plating or striping could be obtained by reversing the positions of the yarns being fed to the needles but this has never proved satisfactory and the devices heretofore suggested are not adapted for use in the modern circular knitting machine where the yarns pass through a throat which changes their direction just before going under the needles.

We have discovered that by putting some tension or drag on first one plating yarn and then the other, under certain conditions each plating yarn can be knit in first on one side of the fabric and then on the other. However, to make a mechanism which will reverse the plating yarns under any conditions, we combine with the tension-alternating feature a reciprocation of the yarn guides radially to the needle circle. The horizontal separation and the reversal of the yarns resulting from this movement of the guides is translated by the throat plate into peculiarly suitable positioning of the yarns as will be set forth in detail later, the whole operation combining to give a very effective striping. Of course stripes of numerous colors can be obtained by feeding a plurality of yarns as backing yarns, and bringing a different yarn to the face with each reversal.

Referring now to Fig. 1, of the drawings, the needles are indicated at N and the throat plate at 559, while the yarn feeding fingers over the throat plate are indicated at F.

These yarn fingers F are pivoted on a cross-pin 554 set in the upright portion of the latch ring 550, the latter being pivoted at a point 552 to the latch ring bracket 401. A separate 5 yarn finger is used for each plating yarn and these fingers are made free to reciprocate radially to the needle circle by passing the crosspin through a slot s in each such yarn finger instead of the customary fitted hole. 10 The yarn fingers can be raised out of feeding relation to the needles by means of the customary thrust bars 460 acting on the under side of the yarn fingers, whenever a change of yarns is desired. These thrust bars 460 are 15 controlled by some of the usual cams on the main pattern drum 120 in any well known manner.

The alternation of the plating yarn fingers between a position near the needle circle and one more distant is accomplished by 20 the mechanism which will now be described. Fastened to the rear end of each plating yarn finger by a screw 11^a is a vertical adjusting plate 11 to whose two ends are respectively 25 attached a link 12 and a tension spring 13. This link and tension spring are each fastened at their other end to a vertical lever bar 14. The connections to each end of link 12 are swivelled.

30 Fastened between a stud 15 on the upper end of the lever bar 14 and a plate p on the upright portion of latch ring is a tension spring 16 tending to hold the lever bar and the yarn finger attached to it forward toward 35 the needle circle. To provide accurate setting of the yarn finger in this forward position there is a screw 12^a mounted in the adjusting plate 11 adapted to act as a stop by touching the upright portion of the latch ring

40 just below the plate p. The method of attachment of the yarn finger to the lever bar just described, permits the yarn finger or the whole latch ring to be raised out of action as usual. Each lever bar is fastened at its 45 lower end to the upper arm of a bell crank lever 17 pivoted on a stud 18 mounted on a bracket m fastened to the frame of the machine. Also mounted on this bracket, near the stud 18 is a shaft 19 which carries rotating

50 pattern control means consisting of an auxiliary or striping pattern drum 20. Also on the shaft 19 is a ratchet wheel 21, the drum and wheel being adjustably fastened together, but free to turn on the shaft 19. On 55 the periphery of the ratchet wheel 21 are teeth, one of them being lower than the others. Inside this striping pattern drum is a spring-pressed friction brake b mounted on the shaft and restraining the drum from accidental 60 movement. On the surface of the drum are cams 22 each adapted to engage the adjustable foot 17^a of the lower arm of one of the bell crank levers 17. When a bell crank lever rides up on one of the cams 22, the upper end 65 of the corresponding lever bar 14 and the

yarn finger connected to it is pulled away from the needle circle. By adjustment of the foot 17^a an accurate setting of the yarn finger in the back position can be obtained. Thus, by alternating the cams 22 operating the two bell crank levers, the two striping yarn fingers can be kept in opposite positions and these positions reversed as desired. 70

The striping pattern drum is turned by a hook plate 23^a on one end of a racking pawl 23 engaging the teeth on the ratchet wheel 21. This racking pawl 23 is swivelled at its other end to a lever 24, pivoted on the frame of the machine. This lever 24 and the racking pawl are reciprocated continuously by a heart shaped cam 25 located on the main drive shaft 32 beside the main bevel gear 31, the engagement between the cam and the lever 24 being by means of a roller 26 on one side of the end of the lever. This roller is held on the surface of the cam by a spring 27 stretched parallel to the racking pawl between the pawl and a guide plate 28 on the bracket m. There is a spring 23^b mounted on the guide plate 28 tending to hold the racking pawl in engagement with the ratchet wheel. The racking pawl 23 lies in a slot in the guide plate 28 and is free to be lifted. The heart shaped cam 25 and the teeth on the ratchet wheel 21 are so cut that at each reciprocation of the racking pawl 23 the striping drum is advanced the length of one tooth on the ratchet wheel. The cams 22 on the striping pattern drum can be made of any desired length, and since the main shaft 32 turns once for every revolution of the needle cylinder, it is possible to reverse the plating after every course or after several courses. 90

In order to stop the rotation of the striping drum when the machine is knitting parts of the stocking where striping is not desired, and for another purpose which will be described later, an idling lever 530 is mounted loose on the shaft 19. The foot of this lever overlies the main pattern drum 120 and is adapted to be lifted by the cams 501 and 502. Projecting upward from this lever to a point just below the racking pawl 23 is an adjustable arm 531. When the idling lever 530 rides up on to a cam 501, this arm 531 is adapted to lift the racking pawl so that the plate 23^a will not engage any of the teeth on ratchet wheel 21. This lifting takes place as the needle cylinder begins to reciprocate to make the heel of the stocking. At the end of the heel the racking pawl is lowered to continue moving the ratchet wheel 21 from where it left off, the pattern thus being unbroken on the instep of the stocking in spite of the insertion of the heel on the back. At the end of the striped pattern in the foot, the striping yarn fingers F are removed from action by the thrust rods 460 and the racking pawl lifted by means of a cam 502 on the main pattern drum. This cam is lower than 100

cam 501 with the result that the racking pawl 23 will continue advancing the ratchet wheel 21 until it comes to the low tooth over which it idles until it is desired to again make 5 striped work. This results in always starting the striped pattern at the beginning of its cycle. Of course there can be several low teeth distributed around the periphery of the wheel 21 if desired. This construction provides 10 independent idling means which can suspend rotation of the pattern drum 20 at any point in the latter's cycle fixed by the ratchet wheel, and also at any point in that cycle designated by the idling means.

15 The idling lever 530 can also be employed to vary the striped pattern by intermittently stopping the rotation of the ratchet wheel 21. The mechanism which operates the idling lever for this purpose is mechanism 20 having angular motion independent of the ratchet means and which can be variably adjusted, as will be described. This mechanism includes means, such for example as a toggle actuated by the usual quadrant or 25 segment gear 75 pivoted on a shaft 76 on which the main pattern drum 120 is mounted (see Fig. 9). This quadrant is actuated from a main drive gear (not shown) by a pitman 70, fastened to the quadrant by a pin 71, and is used amongst other things to actuate the pattern chain. It is geared to make one complete reciprocation for every four revolutions of the needle cylinder. Mounted on the quadrant is a pin 77 held by 30 a set screw 77^a. On the end of this pin is fastened one end of a short bar 532 with a slotted link 533 pivoted at the other end,—this bar and link comprising the toggle.

From one side of the idling lever 530 projects a short pin 534 which lies in the slot 533^a in the slotted link 533. As the quadrant 75 swings away from the ratchet wheel 21 the bar 532 swings the slotted link up and when the pin 534 engages the bottom of the slot 533^a the idling lever is raised and clears the racking pawl from the teeth on the ratchet wheel. The racking pawl is thus made to idle over the ratchet wheel for one or more courses. It will be apparent that by adjusting the position of the dead center of the bar 532 and link 533 in the oscillation of the pivot point of those elements the racking pawl can, for instance, be made to advance the ratchet wheel one tooth and miss the next, 45 advance two teeth and miss the next two, advance three teeth and miss the next one, and advance one tooth and miss the next three, thus altering the number of revolutions of the needle cylinder required to complete one revolution of the ratchet wheel 21. It will be apparent that the pivot point between the link 533 and the quadrant passes dead center between the shaft 76 and the pin 534 during a cycle of the movement of the 55 quadrant. If it is desired to rack every

course the pin 534 is removed from the slot in link 533.

In practical knitting it is necessary to have some tension on the facing yarn but practically none on the backing yarn. We have 70 discovered that it is possible to reverse the plating in certain cases by merely applying tension to the two plating yarns alternately, and feeding them to the needles from approximately the same point on the throat 75 plate, but to make a machine which will reverse the plating under any conditions we prefer to combine the alternating of the tension with the yarn finger control mechanism above described. The tension changing 80 mechanism which we are about to describe is peculiarly effective and simple.

Mounted on the upright portion of the latch ring is a bracket *a* carrying the yarn tensioning mechanism. Each yarn passes 85 between two convex discs *d*—whose convex sides face each other—just before it goes to the toe of its yarn finger (see Fig. 4). Each pair of discs is mounted on a pin *b*, passing through the centre of the discs and the discs are held together by a compression spring *c* whose degree of compression can be adjusted by a thumb-nut *e*, mounted on the pin *b*. The discs are held from turning by a pin *f*, set 90 in notches in the edge of the discs. Each 95 pair of discs, thus mounted, would normally act as a drag on the yarn passing between the discs, but the two pairs of discs are made to release their yarns alternately thus enabling the machine to keep tension on the facing 100 yarn by reversing the tension when the two yarns are reversed. This is accomplished by the means which will now be described.

Pivoted from bracket *a* on the upright portion of the latch ring, is a curved arm *g* having a slanting edge facing the circumference of one of the discs of each pair. When this arm is swung up, the slanting face presses against the edge of one convex disc and pushing against the pressure of the compression 105 spring *c*, tips this disc away from the other, opening a space between the two discs on one side of the pin *b*. The yarn being between the discs on the side of the discs thus opened, has the drag removed from it. In 110 order to operate this tension releasing device, a wire *h* is hooked into the arm *g* at a point above the pivot center of the arm. The wire passes to the rear of the machine, where it passes through the stud 15 on the upper end 115 of the lever bar 14.

To maintain the proper relation between the lever bar 14 and the wire *h*, there is an adjustable collar *j* at the end of the wire *h* with a small tension spring *k* between the sleeve and the plate *p*. The lever bar is held towards the latch ring by a tension spring 16, this having the effect of keeping the arm *g* down and out of engagement with the discs. 120

The plating reversing mechanism operates 125

in the following manner, which ever yarn is acting as the facing yarn being designated as y^1 and the yarn acting as the backing yarn as y^2 . The striping pattern drum is brought 5 into action by the idling lever 530 dropping off its cam 502 on the main pattern drum 120 and letting the racking pawl 23 engage the low tooth on the ratchet wheel 21. The racking pawl being in continuous reciprocation the striping pattern drum starts to 10 turn. The two plating yarn fingers F are dropped into operative position by the thrust bars 460 dropping off their cams on the main pattern drum. Where in the claims we refer 15 to two yarns, it should be understood that we include the possibility of using any number of facing and backing yarns. The yarn finger whose bell crank lever 17 is on a cam 22 then assumes a position away from the needle 20 circle, while the yarn finger whose bell crank lever is off its cam 22 goes to a forward position. For purposes of illustration we shall assume that the parts take the positions shown in Fig. 5. The lever bar 14 which is 25 drawn back pulls the wire h raising the arm g into engagement with the outer disc above it removing the drag on the backing yarn y^2 , (see Fig. 4). The backing yarn y^2 after 30 passing between its two separated discs d goes through the toe of its retracted yarn finger, diagonally over the throat plate, 559 to the corner of the throat 560 and at this point the yarn y^2 turns down to the needles N passing under the hooks of the needles 35 beyond the throat plate in the direction of rotation of the needle circle. The facing yarn however is put under tension by its two discs, and goes through the toe of its yarn finger which is in the forward position. In this 40 way the yarn fingers achieve a horizontal separation of the yarns in a direction substantially radial to the needle circle. The facing yarn y^1 goes out to the throat and over it at a distance from the corner, after 45 which it goes down to the needles, getting under the hooks before the backing yarn y^2 in point of time. From the position of the throat and the needle circle it will be apparent that the two yarns are under the hooks 50 at different elevations as shown in Figs. 7 and 8—Fig. 7 corresponding to Fig. 6 and Fig. 8 corresponding to Fig. 5.

When the cams 22 on the striping drum change alternation the plating yarn fingers 55 reverse their positions in a manner which will be obvious and the arm g which was in engagement with its disc d drops down, releases the disc and puts a drag on its yarn, which now becomes the facing yarn y^1 . At 60 the same moment the other arm g is raised and releases its yarn from tension. The yarn fingers have enough clearance above the throat plate to permit of the yarn which was facing yarn y^1 passing under the other yarn 65 finger as it passes to the corner of the throat

plate. The yarn which now feeds from the forward yarn finger of course goes over the throat at a distance from the corner as the other yarn did before.

The operation of the device for varying the 70 number of courses in each stripe will be obvious from the description already given.

It will be apparent that our invention is applicable to all kinds of knitting machines.

What we claim is:

1. In a knitting machine having rotating pattern control means, a ratchet wheel and pawl, adapted to actuate said pattern means in combination with independent idling means for said pawl adapted to suspend rotation of the pattern means either at any fixed point in the latter's cycle or at any point in that cycle designated by said idling means.

2. In a circular knitting machine having main and auxiliary rotating pattern control means, a ratchet wheel having teeth of two heights and a pawl, said wheel and pawl being adapted to actuate said auxiliary pattern means, in combination with an idling lever for said pawl and cams of two heights on said main pattern means adapted to cause said pawl to idle over the low teeth or all the teeth on the ratchet wheel, substantially as described.

3. In a circular knitting machine having 95 main and auxiliary rotating pattern control means, a ratchet wheel having teeth of two heights and a pawl, said wheel and pawl being adapted to actuate said auxiliary pattern means, in combination with an idling lever 100 for said pawl and cams of two heights on said main pattern means adapted to cause said pawl to idle over the low teeth or all the teeth on the ratchet wheel, substantially as described.

4. In a circular knitting machine having 105 rotating pattern control means and continuously moving ratchet and pawl means therefor, independent means adapted to cause idling of the pawl to begin and end at any point designated by said idling means or at any fixed point of the cycle of said pattern control means, in combination with idling means having continuous angular motion adapted to idle the pawl intermittently.

5. In a circular knitting machine rotating pattern control means and continuously moving ratchet and pawl means therefor, in combination with an idling lever for said pawl, a main pattern control means, cams thereon adapted to raise said idling lever to idling position or to such level that the pawl will commence idling at some point in the cycle of the first mentioned pattern control means determined by the latter, and another idling means having continuous angular motion bearing timed relation to the revolutions of the needle cylinder and adapted to raise the idling lever intermittently to idling position.

6. In a circular knitting machine having 130

- main and auxiliary rotating pattern control means, a ratchet wheel and pawl adapted to actuate said auxiliary pattern means, and an idling lever for said pawl, in combination 5 with cams on the main pattern means adapted to actuate the idling lever to suspend rotation of the auxiliary pattern means both at the completion of the latter's cycle and at any point in that cycle designated by said cams, 10 a quadrant, and means fastened thereon adapted to actuate the idling lever to cause intermittent idling of the pawl during part of the cycle of the quadrant; substantially as described.
- 15 7. In a knitting machine, rotating pattern control means, and continuously moving ratchet and pawl means therefor, in combination with means having continuous angular motion independent of said ratchet means 20 adapted to intermittently hold said pawl in idling position with relation to all the teeth on said pattern control means.
8. In a knitting machine, rotating pattern control means and continuously moving 25 ratchet and pawl means therefor, in combination with means having continuous angular motion independent of said ratchet means adapted to pass over its closest approach to contact with said pawl and back again and 30 thereby intermittently hold the pawl in idling position.
9. In a knitting machine having a quadrant, rotating pattern control means and ratchet means adapted to actuate said pattern 35 means, in combination with mechanism
- including means fastened on the quadrant adapted to cause variable and intermittent idling of the ratchet means.
10. In a knitting machine having rotating pattern control means, ratchet and pawl 40 means therefor and a lever adapted to idle said pawl, in combination with means having continuous angular motion and a link pivotally carried by said angular means having a pivoted connection with said pawl and adapted to idle the latter; the relation of the parts being such that the pivot point of the link with the angular means passes dead center during a cycle of said angular means.
11. In a knitting machine having a quadrant, rotating pattern control means, and a ratchet wheel and pawl adapted to actuate said pattern means, in combination with a toggle comprising a short bar mounted on 50 said quadrant and a slotted link pivoted to 55 said short bar, and a lever adapted to cause intermittent idling of the pawl, the oscillation of the pivot point of the short bar and the slotted link being adjustable with relation to dead center of the toggle, substantial- 60 ly as described.

In testimony whereof we have signed our names to this specification.
